UNITED STATES PATENT OFFICE.

ELI S. REED, OF CHATTANOOGA, TENNESSEE, ASSIGNOR OF ONE-HALF TO
A. J. STOOPS, OF SAME PLACE.

ANTIFILLING DEVICE FOR BOTTLES, &c.

SPECIFICATION forming part of Letters Patent No. 508,342, dated November 7, 1893.

Application filed December 21, 1892. Serial No. 455,907. (No model.)

To all whom it may concern:

Be it known that I, ELI S. REED, a citizen of the United States, residing at Chattanooga, in the county of Hamilton and State of Tennessee, have invented certain new and useful Improvements in Antifilling Devices for Bottles, &c.; and I do hereby declare the following to be a full, clear, and exact description of the invention, such as will enable others skilled in the art to which it appertains to make and use the same.

My present invention refers to a novel and useful bottle-neck or device for use in connection with the necks of bottles of various kinds for the purpose of effectually preventing the fraudulent re-filling with spurious brands of bottles containing originally a genuine article for which the bottle was especially designed, prepared and constructed.

The invention also contemplates other useful objects and purposes, and it consists in the construction, arrangement and combination of parts, substantially as will be herein-after described and claimed.

In the annexed drawings illustrating my invention: Figure 1 is a vertical section of a bottle provided with my improved anti-filling device. Fig. 2 is a detail top plan view of said device.

Similar letters of reference designate corresponding parts in the different figures.

A denotes a bottle, jar, demi-john or other similar receptacle of any desired size and shape and made of any material and designed to contain any desired liquid or article. The bottle A, which is presented merely as an example, has the neck A' of the usual style.

It is to be borne in mind that in many industries using bottles or similar receptacles, special bottles are prepared to contain the liquid or other manufacture and these bottles are specially designed, shaped and marked so that they come to be readily known by the consumer and are easily distinguishable from

other bottles containing a different class of goods. This is notably the case with many kinds of liquors. This practice of using a specially designated bottle has, however, opened the way to fraud and imposition, because parties desiring to deceive will, after emptying the bottle of their original genuine

contents, refill them with an inferior, worthless grade of liquids, quite different from and valueless as compared with the original article and the bottles thus refilled are sold again under the pretense that their contents are genuine to unsuspecting purchasers who are deceived by the appearance of the bottle which outwardly appears to be perfectly genuine, and in this manner the celebrated brand which the purchaser desired to obtain having a mere substitute given therefor, acquires a bad name and suffers an injured reputation. It is to prevent the re-filling of bottles of this character that I have contrived and prepared the present invention.

Within the neck A' sufficiently below the top thereof, not to interfere with the insertion of the ordinary cork, I place a plug B. This plug is preferably made of rubber or other elastic material, although I am not confined to this, but can employ anything else. It is however preferably made of an elastic substance so that it can be crowded tightly into the neck after the bottle has been filled, and when the plug has thus been placed in position the annular ribs or ridges thereon at top and bottom will fit tightly into the annular grooves b in the neck, as shown, thereby fixing plug B more tightly in place. The plug B contains near the bottom end thereof a ball valve C, located within a recess D' which has a small opening c at its bottom in the lower end of plug B and permitting the recess D' to communicate with the interior of the bottle. The opening c is smaller than the size of the ball C, which is adapted either to close said opening by seating itself therein under the action of gravity, as shown in the drawings or to uncover said opening by rolling therefrom into the recess D', a result which takes place when the position of the bottle is reversed. The ball C is therefore loosely placed. It may be of hard rubber or of any other suitable material.

D denotes a curved vertical passage extending from the top of plug B to a point near the bottom thereof where its lower end d connects with the recess D' near the opening c. The lower end d of passage D is accordingly considerably below the upper part of the recess D' so that any liquid poured into the up-

per end of passage D will enter the recess D' and fill it above the ball C and instead of removing the latter from its seat the weight of said liquid will bind it more closely upon its seat in the opening c. It will be observed moreover that the wall of the bottle neck A' is provided at several points (any number) with lateral perforations a a so that if by any possibility the intending fraudulent user of 10 the bottle should dislodge the plug B by pushing it inward or otherwise, he will thereby render the bottle useless, because its neck will then be full of unclosed perforations through which the liquid or fluid will quickly 15 run if the bottle should be put into use.

E represents a vent tube. It is a long tube of suitable diameter and extending from the bottom of bottle A to a point above the plug B. Thus the vent tube E is carried by plug 20 B, running through the latter, the portion which lies within the plug being bent or curved in order that the tube may be more fixedly connected to the plug and less likely to be withdrawn therefrom. The upper end 25 e of vent tube E is located just below the ordinary stopper which will be placed in the mouth of the bottle neck. It will be obvious enough without explanation that liquid cannot be successfully introduced into the bottle 30 through the vent tube and that the latter will perform only the ordinary function of such a tube in permitting a free outflow of the liquid within the bottle A through passage D when desired. The tube E is so placed in plug B 35 as not to interfere with passage D or recess D'. It can be fixed in its position in plug B in any desired manner; and if preferred the plug can be made in sections and the tube placed between them before they are put together.

From the foregoing description, the use as well as the arrangement and construction of my improved anti-filling device will be clearly understood. The bottle will first be filled 45 with the desired liquid or fluid, as for instance, a choice brand of whisky, and then the valve-provided plug will be fixed immovably in the neck of the bottle. Whenever it is desired to empty out a part of the contents 50 of the bottle, it will be lifted up with reversed position, which will cause the valve C to drop from seat c into recess D' and permit an outflow of liquid through passage D. Now after the bottle has been entirely emptied, it can-

not be refilled because whenever such a thing 55 is attempted the ball-valve C will be found to be tightly closing the entrance c to the bottle A, and as access to said ball C, cannot be had from the outside by reason of the curvature of passage D, all admission of liquor into the 60 bottle is effectually prevented. Thus my improved device fulfills the purpose for which it was intended, and prevents the re-use of the bottles with inferior goods.

Having thus described my invention, what 65 I claim as new, and desire to secure by Letters Patent, is—

1. The combination with the bottle neck, provided with the lateral openings, of an elastic plug situated in said neck and held in place by means of annular ribs and grooves, said plug being provided with a recess near its bottom end and a curved vertical passage extending from the top of the plug, to a point near the said recess where the lower end d of 70 said passage is considerably below the upper part of the said recess so that any liquid poured into the upper end of the passage will enter the recess and bind the valve therein more closely upon its seat, together with said 75 valve, substantially as described.

2. An anti-filling device for bottles and the like, consisting in the combination with a bottle-neck having lateral perforations and annular grooves, of the elastic plug B having 80 annular ribs that fit into said grooves and having also the lower recess D' with opening c and the curved vertical passage D extending from the top of the plug to a point near the bottom thereof where its lower end connects with said recess, said lower end being 85 below the upper part of the recess, substantially as described, and the ball C located within the recess and movable therein so as to permit an outflow of liquid which will 90 project it into the upper part of the recess and permit said liquid to flow out through the vertical curved passage, but will prevent the inflow of liquid which will bind the valve more closely upon its seat, all substantially as 95 described.

In testimony whereof I affix my signature in presence of two witnesses:

ELI S. REED.
